[57] CLAIM

The ornamental design for a mount for a cellular antenna, as shown and described.

DESCRIPTION

FIG. 1 is a front, top and right side perspective view of a mount for a cellular antenna showing my new design; FIG. 2 is a rear, top and left side perspective view thereof;

FIG. 3 is a rear elevational view thereof;

FIG. 4 is a left side elevational view thereof;

FIG. 5 is a top plan view thereof, the bottom being a mirror image;

FIG. 6 is a front elevational view thereof; and

FIG. 7 is an elevational view thereof, looking along line 7—7 of FIG. 5; and,

FIG. 8 is an elevational view thereof, looking along line 8—8 of FIG. 5.

FIG. 1

FIG. 2

FIG. 6

FIG. 3

FIG. 4

FIG. 5

7 → 8

FIG. 7

FIG. 8
